VALVE MECHANISM FOR STEAM ENGINES

Daniel S. Dillenbach, Hastings, Nebr.

Application January 2, 1940, Serial No. 312,137

1 Claim. (Cl. 121—164)

This invention relates to a valve mechanism for steam engines of the multiple cylinder type, and has for the primary object the provision of a device of this character for opening and closing the intake and exhaust steam ports of the cylinders in timed relation with the reciprocation of the pistons in said cylinders and which includes slide valves and an operating means therefor actuated by the movement of the pistons which is capable of efficient operation.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary longitudinal sectional view illustrating a portion of a steam engine equipped with a valve mechanism constructed in accordance with the present invention.

Figure 2 is a transverse sectional view taken on the line 2—2 of Figure 1.

Figure 3 is a fragmentary sectional view illustrating one of the cylinders and the intake and exhaust steam passages therefor and the slide valve for controlling said passages.

Figure 4 is a sectional view taken on the line 4—4 of Figure 1.

Figure 5 is a detail sectional view taken on the line 5—5 of Figure 1.

Referring in detail to the drawings, the numeral 5 indicates a cylinder block and 6 a bed or support therefor. Formed in the cylinder block are cylinders 7 in which are reciprocally mounted pistons 8 equipped with connecting rods 9. These connecting rods may be coupled with the mechanism forming the subject matter of my copending application filed December 21, 1939 and Serial No. 310,419, now Patent No. 2,239,663, whereby the pistons will be alternately reciprocated or, if desired, the connecting rods 9 may be coupled to an ordinary crank shaft (not shown). Rack bar operating arms 10 form integral parts of the connecting rods.

The block 5 is provided with intake and exhaust steam passages 11 and 12 connecting with the cylinders 7 and leading outwardly of the block. The passages 11 and 12 are intercepted by valve channels 13 which also open outwardly of the block and have slidable therein valve plates 14 provided with staggeredly arranged intake and exhaust ports 15 and 16. The slidable valve plates also include in their construction rack teeth 17

which mesh with gears 18 secured on shafts 19. The shafts 19 are journaled in bearings 20 carried by vertically arranged supports 21 mounted on the engine bed. Also secured to the shafts 19 are beveled gears 22 meshing with a beveled gear 23 secured to a shaft 24 journaled in a bearing 22. The gears 22 and 23 coact in bringing about reverse rotation of the shafts 19 so that the valve plates will be alternately reciprocated in accordance with the alternate reciprocation of the pistons 8. Integral with the gears 18 are gears 26 larger than said gears 18 and which mesh with rack bars 27 slidably mounted in channels 28 provided in the cylinder block and lie in the path of movement of the rack bar operating arms 10 on the connecting rods 9.

As the pistons reciprocate in their cylinders, operation of the valve plates will be brought about by the mechanism which has been described in detail so that the exhaust ports will be open when the pistons are moving on their non-power strokes and the intake ports closed at that time and when operating on their power strokes the valves will open the intake ports and close the exhaust ports.

Referring to Figure 1 it will be seen that the right-hand piston in this figure has just completed its exhaust stroke and that the intake steam passage is open to admit steam for driving said piston on its working stroke, the other piston being on its exhaust stroke. As the right-hand piston in Figure 1 moves on its power stroke it drives the other piston and as the latter completes a part of its exhaust stroke, the arm 10 thereof contacts one of the rack bars and brings about operation of the valve plates at proper time to close the intake steam passage to the right-hand cylinder and open the exhaust passage thereof and to close the exhaust passage of the left-hand cylinder and open the intake steam passage thereto. Due to the gears 22 and 23 it will be seen that the valve plates are alternatingly operated in accordance with the alternate reciprocation of the pistons 8 and that the shafts of said gears are rotated by the arms 10 striking the rack bars when the pistons are on their non-power strokes. However, it is to be seen that the pistons complete a part of their non-power strokes before the rack bars are engaged and moved by the arms 10 to bring about the actuation of the valve plates. This permits a period of idleness of the valve plates which is needed to permit exhausting of one of the cylinders and admitting steam to the other cylinder when the piston of that cylinder is on its power stroke.

The shafts 19 have secured thereto counter-

balance weights 18' which act to retain the valve plates 14 against accidental sliding movement during the period of time the valve plates are non-driven. The counterbalance weights are arranged to extend in opposite directions from the shafts 19 and assume horizontal positions at the time the valve plates are non-driven. Each time the valve plates are driven the shafts 19 rotate one-half revolution reversing the horizontal positions of the counterbalance weights.

It is believed that the foregoing description, when taken in connection with the drawings, will fully set forth the construction and advantages of this invention to those skilled in the art to which such a device relates, so that further detailed description will not be required.

Having thus described my invention, what I claim is:

In a valve mechanism for steam engines, a cylinder block having cylinders and steam intake 20

and exhaust passages connected to said cylinders, alternately reciprocated pistons in said cylinders and including connecting rods, arms on said connecting rods, shafts rotatably supported on the block and arranged in endwise relation, gearing connecting the adjacent ends of the shafts to bring about rotation of said shafts in reverse direction to each other when either of said shafts is rotated, gears secured to said shafts, rack bars meshing with said gears and slidably mounted in the block and lying in the paths of said arms to be alternately driven by said pistons and thereby alternately drive said shafts, gears secured to said shafts, and valve plates slidably supported by the block and including teeth in mesh with the last-named gears and having intake and exhaust ports for opening and closing the intake and exhaust passages of said cylinders.

DANIEL S. DILLENBACH.
